(57) **CLAIM**

The ornamental design for a spincast fishing reel body, as shown.

DESCRIPTION

FIG. 1 is a top, perspective view of a spincast fishing reel body showing my new design;

FIG. 2 is a left side elevational view thereof;

FIG. 3 is a rear elevational view thereof;

FIG. 4 is a front elevational view thereof;

FIG. 5 is a right side elevational view thereof;

FIG. 6 is a top plan view, at a slightly reduced scale thereof; and,

FIG. 7 is a bottom plan view, at same scale as FIG. 6 thereof. The broken line showing of environment in the drawings is for illustrative purposes only and forms no part of the claimed design.
